UNITED STATES PATENT OFFICE.

MARGARET T. HARTNACKE, OF GRAND RAPIDS, MICHIGAN.

DESIGN FOR A PLAYING CARD.

Application filed August 17, 1928. Serial No. 27,873. Term of patent 3½ years.

To all whom it may concern:

Be it known that I, MARGARET T. HARTNACKE, a citizen of the United States, residing at Grand Rapids, in the county of Kent, and State of Michigan, have invented a new, original, and ornamental Design for a Playing Card, of which the following is a specification, reference being had to the accompanying drawing, forming part thereof.

The figure is a face view of the back of a playing card showing my new design.

I claim:

The ornamental design for a playing card, as shown.

MARGARET T. HARTNACKE.
